DESIGN FOR A SETTEE

Robert I. Anderson, Grand Haven, and Bert Hoeker, Muskegon, Mich., assignors to The Brunswick-Balke-Collender Company, Chicago, Ill., a corporation of Delaware

Application March 13, 1946, Serial No. 127,454

Term of patent 14 years

(Cl. D15—11)

To all whom it may concern:

Be it known that we, Robert I. Anderson and Bert Hoeker, both citizens of the United States, residents, respectively, of Grand Haven, in the county of Ottawa, State of Michigan; and of Muskegon, in the county of Muskegon, State of Michigan, have jointly invented a new, original, and ornamental Design for a Settee, of which the following is a specification, reference being had to the accompanying drawings, forming a part thereof.

Fig. 1 is a perspective view looking at the front of a settee, showing our new design;

Fig. 2 is a perspective view thereof looking from the rear.

We claim:

The ornamental design for a settee, as shown.

ROBERT I. ANDERSON.
BERT HOEKER.
